UNITED STATES PATENT OFFICE.

JOHN J. WILLENBORG, OF PAWNEE, ILLINOIS.

REFRIGERATOR COUNTER.

Application filed February 1, 1927. Serial No. 165,147.

The invention relates to refrigerator counters and has for its object to provide a device of this character having shelves therein, an ice receptacle in a compartment adjacent the upper side of the counter, whereby cold air from the ice receptacle will pass downwardly through the shelving which is preferably formed from mesh material, and thence passed upwardly to the ice receptacle 10 where the heat is again dissipated.

A further object is to provide a refrigerator counter comprising a plurality of compartments having ice receiving receptacle in the compartments adjacent the upper side 15 of the counter whereby cold air will fall through article receiving shelves, and will force the warm air upwardly to be again cooled by ice within the ice receptacle, thereby insuring a natural movement of cold and 20 hot air circulation, and at the same time allowing use in a counter of independent compartments, which is not possible with counters having end icers as at present constructed.

25 A further object is to provide a deflecting member in spaced relation to the rear and bottom sides of the ice receptacle, which deflecting member deflects cold air as it falls forwardly and downwardly to the front of the compartment through shelving whereby the returning warm air will pass upwardly 30 at the rear of the compartment adjacent doors whereby upon opening of a door any loss of air will be from the warm air and not from 35 the maximum cold air.

40 A further object is to provide the partitions between the compartments with ventilating tubes through which the air in its return passes, and through perforations above 45 shelving, thereby insuring a quick and unobstructed return of the air particularly when articles are on shelving adjacent the rear sides thereof.

45 A further object is to provide the downwardly and forwardly extending portion of the deflecting member with a trough in which condensation from the ice receptacle collects, and a drain pipe leading from said trough 50 through the tube to a drip pan in the bottom of the compartment, whereby said cold water will additionally cool the air in its circuit, consequently using said water for cooling purposes at a point in the air circuit remote 55 to the ice receptacle.

55 A further object is to provide a single tube at the divisional walls of the compartments

for forming a return for adjacent compartments, and also to provide perforated return tubes at the outer ends of the end compartments, whereby when additional partitions 60 are placed within the compartments, free circulation is insured for the compartments formed by the partitions.

With the above and other objects in view the invention resides in the combination and 65 arrangement of parts as hereinafter set forth, shown in the drawing, described and claimed, it being understood that changes in the precise embodiment of the invention may be made within the scope of what is claimed 70 without departing from the spirit of the invention.

In the drawings:—

Figure 1 is a front elevation of the refrigerator counter. 75

Figure 2 is a top plan view of the refrigerator counter.

Figure 3 is a vertical transverse sectional view taken on line 3—3 of Figure 1.

Figure 4 is an end elevation. 80

Figure 5 is a perspective view of one of the ventilating tubes.

Figure 6 is a vertical longitudinal sectional view through the counter.

Figure 7 is a vertical sectional view taken 85 on line 7—7 of Figure 3.

Figure 8 is a perspective view of one of the removable partitions.

Figure 9 is a sectional view taken on line 90 9—9 of Figure 8.

Referring to the drawings, the numeral 1 designates the base of the counter which is preferably provided with supporting legs 2. Extending upwardly from the rear side of the base 1 is a rear wall 3, which wall is provided with a plurality of doors 4, through which access may be had to the interior of the compartments 5 of the counter. The number of compartments 5 may vary, however for purposes of illustration three compartments are shown. The compartments 5 are formed by divisional walls 6, the forward portions of which extend to the inclined front walls 7 of the counter, and are preferably formed from glass. Disposed within the compartments 5 at opposite sides of the partitions 6 are ventilating tubes 9, which tubes are provided with a plurality of apertures 10, which are positioned whereby they are spaced above the screened shelves 11, the purposes of 100 which will presently appear.

In refrigerator counters as at present

constructed ice receptacles are placed at the bottom or ends thereof, and when placed at the bottom, they are placed contrary to the natural circulation of the refrigerating plant, 5 as the cold air falls and the hot air rises. When placed at the ends of the counter for maintaining a circuit longitudinally of the counter, it is obvious that partitions for forming independent compartments can not be 10 used, as it will cut off the circulation, and independent compartments are desirable for storing different kinds of foods, particularly those foods which absorb the taste and odors of adjacent foods. To obviate this difficulty 15 ice receiving receptacles 12 are placed in the upper ends of the compartments 5 with their upper ends open, and in spaced relation to the removable closures 13, forming the top of the counter, the rear wall 3 and the front 20 wall 7, and in which receptacles ice is placed. Extending vertically between the rear wall 3 and the rear sides of the receptacles 12 is a deflecting member 14, which is in spaced relation to the wall 3 and the receptacle, thereby 25 forming vertically disposed air passages 15, which terminate in forwardly extending air passages 16 above the downwardly and forwardly extending deflecting member 17, which member 17 is spaced from the under 30 side of the receptacle 12 and above the perforated tube 9, whereby it will not interfere with the passage of air from the upper end of the tube into the compartment. Deflecting member 17 directs the 35 cooled air forwardly towards the forward wall 7 of the counter, so it will fall at the forward end of the counter, and at the same time forms means onto which condensation from the receptacle 12 is collected and down 40 which said condensation flows to the longitudinally disposed trough 18, and through the drain pipe 19, which extends downwardly through the tube 9, and terminates below the bottom shelf 20 within the compartment. 45 The water from the drain pipe 19 is relatively cold and falls onto a plate 21, above a drain pan 22, and by falling on the pan 21 spreads whereby the air in making the circuit in the direction of the arrows in Figure 3 will be 50 additionally cooled by the relatively cold drain water, therefore it will be seen that the cooling properties of the drain water are utilized. The air also passes over the top of the receptacle 12 and falls at the front of the 55 compartment 5.

After the air is cooled and it falls it passes through the shelves 23 and 20, which are preferably formed from screened material and transversely through the compartment 24, 60 then passes upwardly through the portions 11 of the shelves adjacent the doors 4, and also through the tubes 9 and perforations 10 therein. The tubes and perforations allow easy passage of the air, particularly when 65 articles are stored on the shelves adjacent the

doors 4, and in either case air passing through the tubes will be discharged into the rear portion of the chamber. It will be noted that the returning warm air is adjacent the doors 4, consequently when a person opens the 70 door for removing or placing goods therein, cold air is not lost but warm air from the circulating air. It will also be seen that the return relatively warm air passes upwardly in a plane parallel to the plane of the doors, 75 consequently is not directed at an angle which would force the same through the door openings.

The end walls 25 adjacent their rear portions are provided with wooden panels 26, to 80 which are secured ventilating tubes 27 similar to the ventilating tubes 9, and as the ventilating tubes 9 serve the adjacent compartments, it will be obvious that when divisional partitions 28 are shown in Figures 8 and 9 85 are placed on the shelves 20 or within the compartments, said compartments formed by the division members 28 will have return through the tubes 27. Partitions 28 may be of any construction however they are preferably removable, and for purposes of illustration they are shown with channeled rubber members or marginal edges for engaging adjacent parts for maintaining the same vertical. The forward wall 7 of the counter is 90 provided with transparent members 31, through which goods on display at the forward side of the compartment may be seen by customers. However the upper portion of the front wall 7 is provided with mirrors 100 32, which are disposed forwardly of the ice receptacles 12 for obscuring the same from view, consequently preventing the same from detracting from the general appearance of the counter. Access is had to the ice receptacles 12 by removing the covers 13, and in the same manner the ice receptacles may be removed for cleaning and dumping purposes. It is to be understood that coils may be used instead of the receptacles where the cold air 110 is provided by a refrigerating plant.

From the above it will be seen that a refrigerator counter is provided wherein a circulation of cool air is maintained in compartments, the cool air passing downwardly from 115 the cooling element at the forward sides of the compartment, and thence upwardly by the rear side of the counter to the cooling element. It will also be seen that means is provided for preventing free circulation to the 120 perforated tubes, particularly when articles are stored on the shelves, which materially retard the circulation.

The invention having been set forth what is claimed as new and useful is:

1. A refrigerator counter having a chamber therein, shelves within said chamber, an ice receptacle within the chamber and spaced from the upper wall thereof, a deflecting member to the rear of said receptacle and ex- 125 130

- tending under the receptacle in spaced relation thereto, a drain trough carried by said deflecting member, a drain pan in the bottom of the chamber, a drain pipe leading from the 5 drain trough to the drain pan, a vertically disposed perforated tube extending through one of the shelves and resting on the other shelf, said drain pipe extending downwardly through said tube.
- 10 2. A refrigerator counter having a chamber therein, an ice receptacle in the upper portion of said chamber, a deflecting member spaced from the rear side of the receptacle, a downwardly and forwardly extending deflector carried by the first mentioned deflector
- 15 in spaced relation to the under side of the receptacle, and onto which condensation drops, a trough carried by said downwardly and forwardly extending deflecting member, return perforated tubes vertically disposed 20 within the chamber adjacent the rear side thereof, a drip pan in the bottom of the chamber, and a drain pipe connected to said trough and extending downwardly through one of said perforated tubes and discharging into 25 the drain pan.

In testimony whereof I hereunto affix my signature.

JOHN J. WILLENBORG.
